OIL BURNING HEATING STOVE

Wolfgang Julius Magg, Melbourne, Victoria,
AustraliaApplication April 21, 1942, Serial No. 439,812
In Australia December 4, 1941

3 Claims. (Cl. 158—63)

The present invention relates to heating stoves or cookers of the oil burner type wherein the oil fed from the oil container is vaporised by the heat of the metal constituting the burner and in which a burner jet is fitted. One example of the type mentioned is well known under the registered word trade-mark "Primus."

In the type of stove above defined, the jet is arranged in a vertical plane with the burner jet disposed to direct the gas upwardly into the atmosphere disposed above the burner. Consequent upon the disposition stated of the burner jet, the path of the gas issuing therefrom is unidirectional with the flame, whereby the heat of combustion is led away from the metal of the burner which latter is required to be maintained at a temperature operating to cause continuous vaporisation of the oil, the resulting gas being burned at the burner jet.

The present invention has been devised to provide a construction in stoves of the type above-mentioned, wherein the gas issuing from the jet is downwardly directed in contra flow to the flame whereby the heat of combustion is so directed that it impinges upon the metal constituting the burner and during the whole period of operation of the stove the burner is directly located in the heat of combustion to ensure continuous and efficient vaporisation of the oil.

According to this invention a feed pipe leading from the oil container delivers into the neck of the burner which latter is disposed horizontally and the jet of the burner projects downwardly from the latter to be located directly over a flame deflector which is disposed below said jet and causes the direction of the gas to be reversed upwardly and set up a tubular column which impinges upon the burner so that the latter is continuously located in the heat of the flame.

The marginal region of the burner is preferably castellated so that the flame deflected to impinge upon and flowing past the burner is divided into a plurality of jets which during the operation of the stove continuously play on the burner.

The accompanying drawing depicts practical arrangements in accordance with the invention.

In this drawing:

Fig. 1 is a vertical sectional elevation showing the burner with its associated flame deflector and mounted upon the oil container.

Fig. 2 is a top plan, and Fig. 3 an underneath plan of the burner.

Fig. 4 is an enlarged side elevation of the burner and flame deflector.

Referring to Figs. 1 to 4 inclusive, projecting

upwardly from the container 6 is a pipe 7 communicating with the oil in the container and offset for mechanical coupling as by the union nut 8 to the bore 9 of the horizontally disposed neck 5 10 of the circular burner head 11.

The bore 9 of the neck 10 communicates with a vertically disposed bore 12 in the burner head 11, which latter bore is screw threaded to detachably receive the jet 13. The lower face of the burner head 11 registers over the concaved flame deflector 14.

The flame deflector 14 can also be used for the combustion of a volatile fuel such as methylated spirits to heat up the burner head 11 and set up initial vaporization of the oil when starting up the heating stove.

Alternatively a cup such as that provided by the depression at A in the container 6 may be used to receive the volatile fuel mentioned.

20 The lower face of the burner head 11 is castellated as shown so that a circumferential series of passages 15 are provided to set up a plurality of jets of flame from the jet 13 deflected upwardly by the flame deflector 14.

25 The flame deflector 14 is mounted for removal out of register with the lower face of the burner 11 and for that purpose is shown in Figs. 1 and 4 supported by its stem 16 fitted into an aperture in the lower bridging member 17 of a stirrup 18,

30 the upper bridging member 19 of the latter detachably resting in a transverse groove 20 in the upper face of the burner head 11.

In practice I have found that efficient results are obtained by arranging the flame deflector 14 about one half of one inch below the jet 13 with the cross-sectional area of said deflector substantially less than that of the lower face of the burner head 11 with the latter face approximately twice the surface area of the upper face of the deflector 14.

35 In use, when it is required to replace or clean the jet 13, it is convenient to remove the flame deflector 14 out of register with the burner head 11 and consequent upon the inverted arrangement of the jet 13 and the gas being reflected to flow upwardly and about the burner head 11, heat is being continuously applied to the latter and ensures continuity of efficient vaporisation of the oil.

40 Furthermore, on account of the inverted position of the jet 13 there is less liability for dirt or carbon to accumulate therein.

I claim:

1. In an oil burning heating stove of the type specified, an oil container, a vertically disposed

oil supply pipe in communication with and projecting upwardly from said oil container, a horizontal offset from said pipe, a hollow burner head, said head having a horizontal tubular neck connected to said offset and a downwardly delivering jet nozzle, a stirrup supported by and depending from the burner head and including a lower bridging member having an aperture therein, and a flame deflector having a stem removably seating in said aperture to locate the flame deflector below and in alignment with said jet nozzle.

2. In an oil burning heating stove of the type specified, an oil container, a vertically disposed oil supply pipe in communication with and projecting from said oil container, a horizontal offset from said pipe, a hollow burner head connected to said offset said head having a downwardly delivering jet nozzle and a castellated marginal region surrounding said jet nozzle, a stirrup sup-

ported by and depending from the burner head and including a lower bridging member, and a flame deflector arranged on said bridging member below and in alignment with said jet nozzle.

3. In an oil burning heating stove of the type specified, an oil container, a vertically disposed oil supply pipe in communication with and projecting from said oil container, a horizontal offset from said pipe, a hollow burner head connected to said offset, said head having a downwardly delivering jet nozzle and a castellated marginal region surrounding said jet nozzle, a stirrup supported by and depending from the burner head and including a lower bridging member, and a concaved flame deflector on said bridging member below and in alignment with said jet nozzle.
